United States Patent Office

Des. 218,700
Patented Sept. 15, 1970

218,700

HAMPER

Monte L. Levin, New York, N.Y., assignor to Pearl-Wick Corporation, Long Island City, N.Y., a corporation of New York

Filed Aug. 28, 1969, Ser. No. 18,889

Term of patent 14 years

Int. Cl. D7—06

U.S. Cl. D49—8.2

FIG. 1.

FIG. 2.

FIG. 3.

FIG. 4.

FIG. 1 is a front elevational view of a hamper, showing my new design;

FIG. 2 is a left side elevational view thereof;

FIG. 3 is a right side elevational view thereof; and

FIG. 4 is a top view thereof.

The rear wall of the design is flat and void of ornamental features.

I claim:

The ornamental design for a hamper, substantially as shown and described.
